CLAIM

The ornamental design for a belt hanger, as shown and described.

DESCRIPTION

FIG. 1 is a front perspective view of the belt hanger showing my new design;

FIG. 2 is a top and rear perspective view thereof;

FIG. 3 is a bottom and rear perspective view thereof;

FIG. 4 is a front elevation view thereof;

FIG. 5 is a rear elevation view thereof;

FIG. 6 is a side elevation view thereof;

FIG. 7 is an opposite side elevation view thereof;

FIG. 8 is a bottom plan view thereof; and,

FIG. 9 is a top plan view thereof.

The broken lines depict environment and are included for the purpose of illustrating only and form no part of the claimed design.
